UNITED STATES PATENT OFFICE.

WALTER A. ADAMS, OF ROCHESTER, NEW YORK.

WORKBENCH.

Application filed May 17, 1922. Serial No. 531,753.

To all whom it may concern:

Be it known that I, WALTER A. ADAMS, a citizen of the United States, and resident of Rochester, in the county of Monroe and 5 State of New York, have invented certain new and useful Improvements in a Work-bench, of which the following is a specification.

The present invention relates to a work 10 bench or stand designed for use in factories, and an object of the invention is to provide a bench or stand, which may be combined with others, of a like nature, to provide a compact unitary structure for accommodat- 15 ing any desired number of operatives. Another object of the invention is to provide a bench which will be, so formed, that an operative may have her sewing materials within easy reach, provision being made for 20 the convenient disposition of either the finished or unfinished goods. A further object of the invention is to provide a work bench or stand of novel and durable construction.

To these and other ends, the invention 25 consists of certain parts and combinations of parts all of which will be hereinafter described, the novel features being pointed out in the appended claims.

30 In the drawings:

Fig. 1 is a plan view of four combined work benches, constructed in accordance with this invention;

Fig. 2 shows the strand in side elevation 35 of two benches;

Fig. 3 is a fragmentary vertical section through the lower portion of a side frame connecting two benches;

Fig. 4 is a section on the line 4—4, Fig. 3;

Fig. 5 is a section on the line 5—5, Fig. 40 3;

Fig. 6 is a section on the line 6—6, Fig. 3;

Fig. 7 is a detail view of the under side 45 of the clamp for the lowermost support of two benches;

Fig. 8 is a section on the line 8—8, Fig. 3;

Fig. 9 is a sectional view on the line 9—9, 50 Fig. 13;

Fig. 10 is a section on the line 10—10, Fig. 9;

Fig. 11 is a section on the line 11—11, Fig. 17;

Fig. 12 is a section on the line 12—12, Fig. 2 through one bracket;

Fig. 13 is a section on the line 13—13, 55 Fig. 2 with part of one bench broken away;

Fig. 14 is a view of the under side of the uppermost support adjacent the inner ends of two compartments;

Fig. 15 is an enlarged section on the line 15—15, Fig. 14;

Fig. 16 is an enlarged section on the line 12—12, Fig. 2 through one bracket;

Fig. 17 is a fragmentary sectional view of one side frame showing an end of the lowermost support;

Fig. 18 is a section on the line 18—18, Fig. 16; and

Fig. 19 is a fragmentary perspective view of one corner of the side frames.

The embodiment of the invention herein 70 illustrated employs side frames, each of which comprises a front upright portion 1, a rear upright portion 2, a lower connecting portion 3, and an upper connecting portion 4. In order that each side frame may be adjusted so as to be level and horizontally 75 aligned with the other side frames, each upright portion has an adjustable foot 5 (see Fig. 4), these feet having base flanges 6 with slotted bolt openings 7 by which said 80 sockets may be rigidly secured to the support on which the stand rests. Opposite sides and the front edges of these base flanges are notched at 7^a in order that the feet may be aligned with a line on the floor 85 made for aligning all of the side frames. After this alignment is obtained the feet are secured by screws passed through the openings 7^b. An adjustable connection between 90 the uprights 1 and 2 and each foot is obtained by providing the upright with a depending projection 8, operating in the socket of the foot and having a slight lateral movement therein, in order that a set screw 9, 95 operating through the side wall of the socket 5 may force the converging walls 5^a of the socket, into binding engagement with the converging walls 8^a of the depending projection 8. The socket of each foot and the projection are made non-circular, so as to 100 prevent the turning of the foot. It is preferred to cut away the flange 6 on one side, in order that the flange will not project beyond the uprights 1 and 2, and that the vertical surfaces 5^b on the rear feet of two 105 frames arranged back to back may abut.

The lower connecting portions 3 of the two frames are detachably connected together by connecting pieces or supports 10, 11 and 12, preferably in the form of boards 110 resting on the upper surfaces of the con-

necting portions 3, the connecting portions preferably being deflected downwardly toward the front of the bench and the board 10 resting upon the said downwardly deflecting portions of two side frames, and serving as a foot board for the operative. The boards 11 and 12 may act as supports for any object or article used by the operative. In order that these lower supports 10, 11 and 12 may be firmly held to the connecting pieces 3, a clamping bar 13 is provided for each side frame. When two benches are connected to one side frame, a clamping bar like that shown in Figs. 3, 5, 6, 7 and 8 may be employed. This clamping bar at its rear end is slotted at 14 to straddle the flange or rib 15 on the rear upright 2 and is slotted at 16 to straddle the flange or rib 17 on the upright 1. The under side of this bar 13 may be provided on its under side with spacing devices 19 for entering between the supports 10, 11 and 12. Longitudinal ribs 18 may be provided on the under side of the clamping bar midway between the side edges thereof for limiting the longitudinal movements of the supports 10 and 11, while the longitudinal movement of the support 12 is limited by the vertical flange 15 on the inner face of the upright 2. With the end in view of holding each clamping member to its connecting piece 3, the connecting piece may be provided midway between its ends with a bolt opening 20, while the clamping bar or member is provided with a bolt opening 21. A bolt 22 extends through both these openings and secures the clamping bar in position. The opening 21 is situated in one of the spacing ribs 19, so that it will not interfere with the seating of the connecting pieces 10, 11 and 12 on the horizontal connecting piece 3.

At the end of a series of benches or when only one bench is employed, a clamp 13^a (Figs. 11 and 17) is employed. This clamp has the ribs 18^a for engaging the ends of the connecting pieces 10 and 11. A rib 18^b is provided which rests upon the connecting portion 3 and beyond said rib a downwardly turned flange 18^c is provided, which gives a finish to the end of the bench. The clamp is secured by a bolt 22 in the same manner as the clamp 13 and it is notched at its ends at 14^a and 16^a to receive the flanges 15 and 17 on the inner sides of the uprights 2 and 1 respectively.

Each side frame preferably has its upper connecting portion extended at 4^a beyond the upright 1 and on this upper connecting portion 4 with its extension 4^a a supporting member or board 23 is secured preferably by providing the upper portion 4^a and its extensions with laterally slotted enlargements 24 through which screws 25 pass. This support extends transversely of the

bench and lies over the lower supports 10, 11 and 12, while projecting in front of the latter, so that an operative may sit between two of such supports and place the finished or unfinished goods thereover. 70

In order that two side frames may be fitted together back to back, each side frame has a machined spacing lug 26, projecting from its rear upright 2, and this rear upright also has (see Fig. 19) near its upper end horizontal slots 27 in opposite sides. A spacing plate 28 is fitted between the two side frames and this spacing plate has openings through which bolts 29 extend, the spacing plate thus serving to hold the bolts 80 against accidental release from the slots 27 in the event that the bolts should become loose.

There may be also provided in connection with each bench an upper support 30, which, in this embodiment of the invention, is common to two operatives, being supported at opposite ends on brackets 31, each of which is supported in the illustrated embodiment on two side frames arranged back to back. 85 In order that these brackets 31 may be supported on two side frames, arranged back to back, each of the side frames is provided on its horizontal connecting portion 4 with a horizontal surface 32 in rear of the transverse support 23, the opposite sides of the side frame being provided with notches 33 (see Fig. 19) in the portion having the surface 32. The bracket 31 has near its center a transverse lug 34 which projects downwardly between the side frames and acts to space the latter. This bracket 31 also has notches 35 in opposite sides and through these notches and the notches 33, bolts 36 extend, these bolts being held in the notches 33 and 35 by passing through openings in plates 37 (see Figs. 2, 16 and 18). 90

The upper supports 30 (see Figs. 9 and 10) are secured to the brackets 31 preferably by slotting said uprights at 38 at their upper ends and providing seats 39 on opposite sides of said slots and upwardly turned portions 40 on the outer sides of said seats. The width of each of these supporting portions 39 is sufficient to permit the ends of the two supports 30 to be secured thereto, said supports 30 being held in position on the seats by screws 41 passing through the latter and into the supports 30, so that two supports 30 may be secured thereto. At the end of a number of benches short pieces 30^a (see Fig. 1) may be secured to the seats 39 to give a finished appearance to the bench. 100

Each bench may be provided with a compartment for the reception of materials and articles used in connection with the work. In this embodiment of the invention, this result is secured by providing two cross pieces 42 secured in spaced relation transversely of the support 30 to project from 115 120 125 130

opposite sides of the support 30 in order to form the side walls of two compartments. These side walls are connected to outer pieces 43 forming the outer walls of the 5 compartments and inner pieces 44 forming the inner walls of the compartments, bottoms 45 being provided for each compartment. The side pieces 42 are notched, so as to receive the support 30 (see Figs. 14 and 10 15), and the rear walls 44 abut the under side of said support 30. With the end in view of firmly securing the compartments to the support 30, a securing frame 46 may be provided preferably of cast metal of 15 rectangular construction and formed to fit between the side piece 42 and the rear walls 44, this frame being secured to the support 30 and having portions 47 projecting laterally therefrom to engage under the rear 20 walls 44 and the side walls 42 of the compartments. Screws 48 secure the frame 46 to the under side of the support 30.

In order that electrical fixtures may be used in connection with the bench, each support 30 has a central opening 49 with a 25 metal collar 50 secured to the top surface of the support about said opening, this collar being internally threaded and being adapted to be engaged by a conductor tube 30 51 which extends through the opening 49 and an opening 52 in the supporting frame 46. An elbow or other coupling device 53 is secured to the lower end of the conductor tube and abuts the under side of the supporting frame 46, in order to also serve for 35 securing said frame to the support 30. With the elbow 53 or coupling device another conductor tube may connect preferably leading under the support 30 and through 40 the opening 38 in the uprights 31.

From the foregoing it will be seen that there has been provided a work bench which may be either used as a single unit or may be combined with other benches to provide a 45 single longitudinal structure, or may be united with other benches back to back. This construction enables the building at a small expense and at a short time of a desired number of benches in a compact space. 50 A side frame is provided which is adapted to form a common side frame for two benches. Each side frame has two uprights connected by a lower connecting member on which the lower supports or boards of two 55 benches may rest. A clamping means is employed in connection with this lower connecting piece which spaces the lower supports or boards apart and, at the same time, firmly holds the board pieces to the side 60 frames without the use of separate securing devices for each board. Each side frame also has an upper portion connecting the upper ends of its uprights and projecting 65 forwardly from the front upright to support transversely extending supports, which

will be utilized for any suitable purpose by the operative, the latter sitting between two of said transversely extending supports and using the lower supports or boards between the lower portions of two side frames as a 70 rest for the feet or for the holding of any suitable articles or materials used in connection with the work. Provision is made for securing two side frames back to back, so that two benches may be arranged in a 75 compact structure back to back. Detachably supported on the side frames and, in this instance, one or each two side frames arranged back to back are supporting brackets which are provided with means for spacing 80 the two side frames apart and also for holding them in fixed relation. These supporting brackets are connected by upper supports, each supporting bracket being adapted to sustain the abutting ends of the 85 two supports. Supported on the upper support is a compartment projecting forwardly from said support toward the user of the bench. Two compartments have, in this 90 instance, common sides and between these sides and also the rear walls of the two compartments a frame is arranged which firmly secures the two compartments to the upper support.

What I claim as my invention and desire 95 to secure by Letters Patent is:

1. A work bench comprising two side frames, a lower horizontal and longitudinally extending support having a wide surface on which articles or other material may be supported connecting said side frames, and two elongated horizontal and transversely arranged article supports on the side frames above the lower horizontal and longitudinally extending supports, said upper two 100 horizontal and transversely extending supports being spaced apart and projecting forwardly beyond the front edge of the lower support. 105

2. A work bench comprising two side frames, a lower horizontally and longitudinally extending support connecting said side frames and having a wide surface on which material or other articles may be supported, two elongated horizontally and transversely extending article supports supported on said side frames in a plane above the lower support, said horizontally and transversely extending support projecting beyond the front edge of the lower support and spaced apart 110 to provide an open space between the supports, and a horizontal support supported by the side frames, extending the full distance between them longitudinally of the bench and lying in a plane above the transversely extending supports with its forward edge in rear of the forward edge of the lower longitudinally extending support. 115 120

3. In a work bench, the combination with 125 two side frames, each comprising two up-

rights, a lower horizontal connecting member between the uprights, an upper connecting member between said uprights, an extension projecting beyond each front upright 5 and forming a continuation of the upper connecting member of the side frames; of a lower horizontally and longitudinally extending support connecting the lower connecting members of the two side frames and 10 having a wide surface on which the material or other articles may be supported, and two elongated article supports extending horizontally and transversely of the bench and each secured to the upper connecting member of a side frame and to an extension, the two transversely extending article supports being spaced apart to provide an opening 15 in which an operative may work.

4. In a work bench, the combination with 20 two side frames each comprising a front and a rear upright, a lower connecting member between the uprights, and an upper connecting member between the uprights; of a lower support connecting the upper connecting member between the side frames and having a wide surface on which material or other articles may be supported, and elongated supports arranged horizontally and extending transversely of the bench, said elongated supports being secured to the upper connecting members of the two side frames projecting beyond the front uprights of said side frames and being spaced apart so as to provide a space in which an operative may 25 work.

5. In a work bench, the combination with two side frames each comprising a front and a rear upright, a lower connecting member between the uprights and an upper connecting member between said uprights; of a lower horizontal support connecting the lower connecting members with the two side frames having a wide surface on which material or other articles may be supported, 40 two elongated transverse article supports each secured to the upper connecting member of a side frame and projecting forwardly beyond the front upright of said side frame, the two transverse article supports being spaced apart to provide a space in which an operative may work, two brackets each detachably secured to one of the side frames in rear of the transverse support thereon, and an upper horizontal support connecting 45 said brackets above the transverse supports, the forward edge of said horizontal support being in rear of the forward edge of the lower support.

6. In a work bench the combination with 50 two side frames, each comprising a front and a rear upright, a lower connecting member between the uprights and an upper connecting member between said uprights, of a lower support connecting the lower connecting members of the two side frames having

a wide surface on which materials or other articles may be supported, two elongated transversely extending article supports each secured to the upper connecting member of a side frame and projecting beyond the front 70 upright of such side frame, said elongated supports being spaced apart to provide a space in which an operative may work, two brackets each secured to one of the side frames in rear of the transversely extending 75 supports thereon, an upper horizontal support connecting said brackets above the transverse supports and having its forward edge in rear of the forward edge of the horizontal support, and means projected forwardly from the upper support in vertically spaced relation from the edges of the elongated transverse supports and provided with a compartment in which suitable articles 80 may be received.

7. The combination with two pairs of side frames, the members of each pair being arranged back to back and each side frame embodying a rear upright and a front upright, a lower connecting portion between the uprights of each frame, an upper connecting portion between the uprights of each frame, a lower support connecting the lower connecting portion of a side frame of one pair with a lower connecting portion of a side frame of the other pair, transverse supports each secured to the upper connecting portion of a side frame and projecting forwardly beyond the front upright of said side frames, two brackets each secured to the two members of a pair of side frames and projecting upwardly above said side frames, and an upper support connecting the two brackets.

8. The combination with two pairs of side frames, the members of each pair being arranged back to back, and each side frame embodying a rear upright and a front upright, a lower connecting portion between the uprights of each frame, an upper connecting portion between the uprights of each frame, a lower support connecting the lower connecting portion of a side frame of one pair with a lower connecting portion of a side frame of the other pair, transverse supports each secured to the upper connecting portion of a side frame and projecting forwardly beyond the front upright of said side frames, two brackets each secured to the two members of a pair of side frames and projecting upwardly above said side frames, and an upper support connecting the two brackets each of said brackets having a spacing projection extending therefrom between the two members of the pair of side frames 110 to which said bracket is secured.

9. The combination with two pairs of side frames, the members of each pair being arranged back to back, of upright brackets, each secured to the two members of a pair 115

of side frames and projecting above said side frames, said brackets each having a spacing projection extending therefrom between the two members, of the pair of side frames to which said bracket is secured, and a horizontal support connecting the two brackets.

10. In combination with a horizontal support, two compartments projecting from opposite sides of said support, each compartment having two of its side walls connected to two of the side walls of the other compartment, the connecting portions extending beneath the horizontal support, and a frame secured to the under side of the horizontal support and engaging with said side walls to hold the two compartments to the horizontal support.

11. In combination with a horizontal support, of two compartments projected from opposite sides of the supports having their side walls connected and arranged under the support and their back walls arranged in spaced relation, and a frame secured to the under side of the support and engaging said compartments to sustain them on the support.

12. In combination with a horizontal support, two cross pieces extending transversely of said support and projecting from opposite sides thereto to provide side walls for two compartments, front walls connecting the outer ends of the cross pieces, rear walls connecting the side pieces beneath the horizontal support, a bottom wall for each compartment, and a frame secured to the support and having portions engaging the rear walls of the compartments and the transversely extending cross pieces in order to support the compartments from the support.

13. In combination with a horizontal support, two transversely extending cross pieces arranged beneath the support and extending from opposite sides thereof, two pieces connecting the ends of the two transversely extending pieces and forming the front walls of two compartments, two pieces connecting the transversely extending pieces and forming the rear walls of the compartments, bottom walls for the compartments, and a rectangular frame secured to the under side of the horizontal support and having portions extending under the transversely extending cross pieces and also under the rear walls of the compartments to hold the compartments to the horizontal support.

14. In combination with a horizontal support a compartment projecting from said

support having side pieces extending under the support, and a frame secured to the under side of the support and having portions engaging said side pieces to sustain the compartment on the support.

15. A work bench comprising side frames, lower horizontally arranged supports connecting said side frames and having a surface on which the material and other articles may be supported, and upper transversely extending article supports projecting beyond said side frames transversely of the lower supports, and the bench opening vertically upward from the lower horizontal and longitudinally extending support above the two upper horizontal and transversely extending supports, so that an operative may work between such transversely extending supports, an upper article support arranged longitudinally of the bench in a plane above the transverse supports and a compartment projecting forwardly from said uppermost support.

16. A side frame for work benches comprising uprights a lower connecting member between the uprights, clamping means extending from one upright to the other for securing the ends of supports to said connecting member, an upper connecting member between said uprights, and an extension forming a continuation of the upper connecting member.

17. A work bench having lower article supporting means extending longitudinally of the bench substantially throughout the length thereof, two upper article supporting members at opposite ends of the lower supporting means extending transversely of the bench over the lower supporting means and projecting beyond the front edge of said lower supporting means, and a bench opening vertically upward from the lower horizontal and longitudinally extending support above the two upper horizontal and transversely extending supports, so that an operative may work between such transversely extending supports, and a compartment arranged in a plane above the transversely extending supports in a position between said supports and over the lower supporting means.

18. In combination with two frames each provided with notches on opposite sides, a spacing plate arranged between the two frames provided with bolt openings, and bolts extending through said openings and lying in the notches of the two frames.

WALTER A. ADAMS.
